UNITED STATES PATENT OFFICE.

GEORGE R. MACINTIRE, OF NEW YORK, N. Y., ASSIGNOR OF ONE-HALF
TO ELLIOTT P. GLEASON, OF SAME PLACE.

DESIGN FOR AN ELECTRIC LAMP.

SPECIFICATION forming part of Design No. 29,368, dated September 20, 1898.

Application filed March 18, 1898. Serial No. 674,391. Term of patent 14 years.

To all whom it may concern:

Be it known that I, GEORGE R. MACINTIRE, a citizen of the United States, residing in the city of New York, in the county and State of New York, have invented a certain new and original Design for Electric Lamps, of which the following is a specification, reference being had to the accompanying drawings, forming a part thereof.

- 10 This invention relates to electric lamps in the complete form in which they are used and of which the shade or reflector may be regarded as forming a part.
The invention consists in the design for such lamps to be described more fully hereinafter.
15 The accompanying drawing presents a side view of a lamp which embodies the design.
The main portion of the lamp, as seen in

side view, is an inverted-bell shape A, with a somewhat sharply-spreading corrugated 20 edge portion a. Above the upper edge of the portion A is the projecting portion of an ovoid B.

The characteristic feature of the design is the inverted-bell shape A, with the corrugated 25 spreading edge a, with the projecting portion of an ovoid B.

What I claim is—

The design for an electric lamp, substantially as shown and described. 30
This specification signed and witnessed this 15th day of March, A. D. 1898.
GEORGE R. MACINTIRE.

In presence of—

A. N. JESBERA,
F. M. EGGLESTON.
